United States Patent

Des. 240,337
Patented June 22, 1976

240,337

URINE METERING AND COLLECTION UNIT

Paul Hanifl, Warwick, R.I., assignor to International
Paper Company, New York, N.Y.

Filed Mar. 10, 1975, Ser. No. 557,033

Term of patent 14 years

Int. Cl. D24—04

U.S. Cl. D83—1 U

FIG. 1

FIG. 2

FIG. 3

FIG. 4

FIG. 1 is a front elevational view of a urine metering and collection unit embodying my new design.

FIG. 2 is a top plan view of the urine metering and collection unit of FIG. 1.

FIG. 3 is an end view of the unit of FIG. 1.

FIG. 4 is a rear view of the unit of FIG. 1.

I claim:

The ornamental design for a urine metering and collection unit, as shown.
